8 Claims. (Cl. 139—336)

1

This invention relates to improvements in looms for weaving, and while the invention, either wholly or in part, may readily be applied with suitable and obvious adaptation to any kind of loom, it is particularly applicable, and will be herein described in particular reference, to heavy looms of exceptional width, such as looms for weaving papermakers' felts.

In such looms, the reed-width of which ranges from about 20 feet to over 50 feet, the ordinary well-known construction of warp and shuttle protector mechanism is far from satisfactory. This known mechanism consists of a long shaft or stop-rod mounted in bearings on the slay or the slay-swords, which stop-rod is provided with a finger-lever bearing on the shuttle-box swell at each end, and also with one or more forwardly projecting blades or daggers, which latter, when the shutter fails to enter a box and open out the swell at the proper time in the slay's forward movement, engage a corresponding number of abutments or frogs supported more or less resiliently on the framework and/or the breast-rail of the loom, and thus act directly to arrest the slay in its forward movement, also concurrently to stop all other moving parts of the loom.

These daggers and frogs, also the supports for the latter, are subjected to very severe impact loads which, especially in the case of heavy and wide looms, cause frequent damage to the parts involved, with resultant expense for repairs, coupled with serious loss of production.

The initial engagement of the daggers with the frogs, and the corresponding displacement of the latter (or one of them) is usually arranged to displace the starting-handle from the catch or toggle-lock which normally retains the handle in the "run" position, the object being to allow a loaded spring, or in some cases an elevated weight, to act to disengage the driving clutch and thereby to reduce the load imposed on the frogs, and further with the same general object, to apply a friction brake fitted to one of the revolving shafts of the loom, usually the crankshaft, or some other shaft revolving at a speed much lower than that of the electric motor employed for driving the loom.

The intended purpose of the said spring is to accelerate the starting-handle and linkage connections leading therefrom to the clutch and brake, together with the controlling parts of these latter, so as to return them as quickly as possible to their "stop" positions with the above stated object.

Manual operation of the starting-handle from

2

the "stop" to the "run" position involves, however, not only overcoming the brake-spring pressure (which increases in some degree during such movement), but also exerting the additional pressure needed to engage the clutch. In practice, therefore, the pull of this spring is strictly limited to accord with the maximum manual effort permissible for operating the starting-handle.

For the reasons stated, therefore, the retarding action provided by the ordinary loom brake of known construction, even assuming this could be instantaneously applied, is very much less than that required to stop the moving parts of a loom with the necessary promptness to enable a friction-brake to replace the sprag-action of the customary dagger and frog mechanism.

In addition, moreover, to the ordinary loom brake's inadequate stopping power, there is an unduly long delay or time-lag between the dagger's initial engagement with the frogs and completion of the operational sequence comprising disengagement of the clutch and full application of the brake, even when this operation is performed under the action of a loaded spring, such delay consisting of, firstly, the time taken to displace the starting handle from its catch and, secondly, the time taken by the limited spring pressure available to overcome the inertia of the relatively heavy parts and return them to their respective "stop" positions.

If the brake is applied by the release of an elevated weight, instead of a loaded spring a still longer time-lag in attaining full application of the brake is unavoidable, because of the limited acceleration of the falling weight in comparison with that provided by a suitable spring.

In the known constructions, the frogs, therefore, not only absorb the momentum of the moving parts of the loom, but also oppose the driving effort of the motive power until the clutch begins to slip in the course of its disengagement, and, in fact, the loom slay and other parts have usually been brought to a standstill by the frogs alone by the time, if not before, the loom friction brake of known construction has been brought into action.

The driving clutch, of course, may be so arranged that it will slip if subjected to a torque somewhat in excess of that to be transmitted in order to drive the loom at its normal speed, the object being to ensure that the clutch will start to slip immediately the daggers engage the frogs. While this may ease the problem in some degree as regards the frogs and their supports, it cannot be accepted as a satisfactory solution, because a

clutch, if adjusted in such manner, will be liable to slip during the development of each picking impulse, and furthermore, will require a longer time, when starting, to bring up the loom to its normal running speed.

Quite irrespective of the method to be employed for arresting their motion in the stated or similar circumstances, it is obviously beneficial to reduce to the practicable minimum the inertia, and therefore, the momentum, of the whole of the loom parts which have to be brought, very quickly, to a complete standstill. Heavy flywheels, for example, which in some cases are fixed on the loom crankshaft multiply the hereinbefore described difficulties, and, therefore, simply cannot be tolerated.

In heavy looms of exceptional width, a control rod is usually fitted along the breast-rail, and, at the driving end of the loom, is hinged to the starting-lever which controls the action of the clutch and brake. The purpose of the said control rod is to enable the weaver to start and stop the loom from any position along the loom front, an obvious convenience in the case of wide looms.

While this control rod is readily operated by hand for ordinary starting and stopping purpose, its inertia, which is very considerable, causes, in the case of automatic stopping, a serious increase in the time taken by the brake-spring to return the starting-lever, together with its attached parts, to the "stop" position. Even when a control rod is not used, the inertia of the ordinary starting handle causes an appreciable delay action prejudicial to very prompt stoppage of the loom under automatic control. Such increased time-lag in disengaging the clutch intensifies the load on the frogs and also prolongs the period of its application thereon.

Heavy and wide looms employed for weaving paper makers' felts are almost invariably of the "pick-at-will" type with drop-boxes at both ends of the slay. Weft failure due to breakage of weft or exhaustion of the shuttle package, unless detected immediately by the weaver and appropriate action taken, results in serious delays due to the consequent unweaving and finding of the correct shed to enable weaving to be continued. In spite of these production delays, however, such looms have not hitherto been satisfactorily equipped with weft-fork stop-mechanism, mainly for two reasons, the first being the difficulty presented by the necessity of stopping the loom automatically by reason of weft failure with the essential promptness to be of real practical value, and the second being that none of the known so-called "centre" weft-fork motions satisfactorily fulfils the requirements.

In many known weft-fork stop mechanisms, reliance is placed upon gravity, in some cases aided by a light spring, to effect the whole of the fork's downward movement. In such construction, therefore, the fork is liable to be held up by the frictional resistance of a strong and dense warp, while if weighted or provided with a heavier spring to ensure its proper descent through the warp, the fork would impose a greater load than the weft could satisfactorily support, in either arrangement the operation being unreliable. Furthermore, the fork movement is usually derived from that of the slay, with the result that the operation must be timed as permitted by the motion and not vice versa as is obviously desirable, while in most cases the action involves such undesirable delay that the slay is close to or actually in its front position before displacement

of the starting handle from its catch has been effected.

The main object of the invention is to provide improved means for driving, stopping and, in certain circumstances, reversing looms, especially heavy looms of exceptional width, such driving means under manual control bringing up the crankshaft and co-driven parts to their normal running speeds in a short period of time corresponding to about 60 degrees or less of the crankshaft's revolution, and such stopping means, under either manual or automatic control or both disconnecting the drive and arresting all the moving parts of the loom, including the slay, in a short period of time corresponding to about 30 degrees or less of the crankshaft's revolution, such said stopping means being initiated automatically by reason of either the shuttle failing to enter the shuttle-box at the proper time or any one of a number of weft-forks detecting the absence of weft in the shed at or shortly before the time when the shuttle is normally due to enter the box, and such reversing means, under manual control, enabling the slay, after it has been so arrested in its forward movement to be returned at will to its back position, or thereabouts, during which movement the crankshaft and its co-driven parts are caused to make a partial revolution in the reverse direction, thereby re-opening the last shed in which the fault occurred.

A further object of the invention is to provide a novel combination comprising a flywheel, a friction clutch and a friction brake, the flywheel and clutch outer member being mounted on a short primary shaft which is supported in suitable bearings and driven by an electric motor (preferably by a flexible coupling) either at or about the same speed as that of the electric motor, whereby the flywheel, clutch and brake all have maximum effectiveness for their respective purposes. A secondary shaft, also supported in suitable bearings in axial alignment with the said primary shaft, has mounted on it the inner member of the clutch and also the inner member of the brake, the outer member of which latter is prevented from revolving, and may be part of, or attached to, a casing provided to enclose the flywheel, clutch and brake. A common shipper, slidably mounted on the secondary shaft between the two said inner members, serves to disengage the brake and engage the clutch, and vice versa, so that either the said secondary shaft may be clutched to and driven from the motor-driven primary shaft, the brake being first disengaged, or alternatively, the secondary shaft may be de-clutched and promptly stopped by engagement of the brake under action of a loaded spring. The said flywheel, clutch and brake, due to their relatively small physical dimensions as a direct consequence of their operation at or about the speed of the electric motor, provide an unusually compact assembly, while the manual effort required to release the brake, against the action of the said spring, and to engage the clutch, is reduced to an absolute minimum in relation to the desired stopping power of the brake.

In looms of the drop box type the changing movement of the shuttle-boxes is liable to be impeded by a misplaced shuttle or by a damaged picking stick or picker and in order to prevent breakage of the parts, it is usual to include a safety escapement in the actuation linkage of each set of boxes, each such escapement being self-releasing upon overload caused by the jamming of its associated set of boxes.

When a set of boxes jams in this manner, the picking mechanism at the same end of the loom is in turn impeded, because in such circumstances the picker cannot enter, as it normally does, one of the slots provided in the backs of the boxes. To prevent damage to the picking mechanism and associated parts it is common practice to incorporate therein some suitable form of safety escapement which will release automatically upon overload.

With the construction of loom drive hereinbefore referred to as forming an object of the present invention comprising a clutch and brake operating at or about the speed of the electric motor used to drive the loom, which clutch is disengaged and the brake applied with exceptional rapidity by means of a loaded spring, consequent upon the tripping, by automatic means, of a secondary toggle included in the linkage connecting the loom starting-handle (or its equivalent) to the shipper lever which actuates the clutch and brake and having means whereby the secondary toggle may be tripped automatically by reason of (1) the shuttle failing to enter the box at the appropriate time in the slay's forward swing, or/and (2) the absence of weft in the shed as detected at or about the time when the shuttle is due to enter the box after its flight across the loom in either of such events the slay being promptly arrested in its forward swing, it is possible to provide means, and the provision of such means form a further object of the invention whereby the moving parts of the loom will be automatically and promptly arrested in the event of either set or both sets of boxes jamming during their change movement, such stoppage of the loom being initiated when the slay is approximately in its most forward position (when the boxes are about half-way through their change movement) and thereafter completed before the loom crankshaft has revolved sufficiently further to effect commencement of the next picking operation.

The means according to the invention for achieving the aforesaid object comprise mechanical linkage connections of any convenient form between the usual box-motion safety escapement and the aforesaid secondary toggle, whereby the latter will be tripped consequent upon the automatic release of either of or both such escapements, and all the moving parts of the loom promptly brought to rest with the slay having swung back only about one third to one half of its sweep from its most forward position.

The invention is illustrated in and will be described with reference to the accompanying drawings in which:

Fig. 1 is a longitudinal section showing the assembly of the high-speed flywheel, clutch and brake, also worm-gear box;

Fig. 2 is a cross-section of the clutch and brake assembly showing their common operating lever;

Fig. 4 is a part end-elevation of a wide loom showing the driving arrangements according to the present invention;

Fig. 5 is a plan corresponding with Fig. 4;

Figs. 6a, 7a, and 8a, are elevations showing the primary and secondary toggle mechanism, also the tripping mechanism, in various positions;

Figs. 6b, 7b, and 8b are plans corresponding respectively with Figs. 6a, 7a and 8a;

Fig. 9 is a broken front elevation of the left-hand end of a loom slay showing the light stop-rod fitted with dog and dagger;

Fig. 9a is a view similar to Fig. 9 but showing the right-hand end of the loom;

Fig. 10 is a cross-section corresponding with Fig. 9;

Fig. 10a is a plan of the dog and dagger;

Fig. 11 is a broken front elevation of a loom slay showing the weft-fork and co-ordinated stop-rod mechanism;

Fig. 11a is a transverse section of Fig. 11.

10 Figs. 12, 13 and 14 are cross-sections showing the weft-fork mechanism in various positions;

Figs. 12a, 13a, and 14a are details illustrating the weft-fork action;

15 Figs. 12b and 13b are details to illustrate the spring escapement action;

Fig. 15 is a part cross-section through a loom showing the assembly of the weft-fork cam-actuated mechanism;

Fig. 16 is a timing diagram, and

20 Fig. 17 is a part cross-section through a loom showing the use of springs or weights to return the slay to its rear position;

Fig. 18 is an end elevation of a well-known arrangement of box-motion transmission levers embodying a safety-escapement;

Fig. 19 is a similar view with the box-motion transmission levers in a different position;

Fig. 20 is a similar view showing the safety escapement in action;

30 Fig. 21 is a plan showing the said box-motion transmission levers and certain added parts according to the present invention;

Fig. 21a is a detail of the feeler-lever and co-acting trip-bowl;

35 Fig. 22 is a front elevation, partly in section, showing means for the automatic displacement of the aforesaid trip-bowl;

Fig. 23 corresponds with Fig. 5 and is a part cross-section viewed from inside the loom end-frame, and

40 Fig. 24 is a timing diagram to illustrate the action of the safety device illustrated in Figs. 18 to 23.

As previously stated the main object of the 45 invention is to provide improved means for driving, stopping and, in certain circumstances, reversing looms, especially heavy looms of exceptional width, such driving means under manual control bringing up the crankshaft and co-driven parts to their normal running speeds in a short

50 period of time corresponding to about 60 degrees or less of the crankshaft's revolution, and such stopping means, under manual or automatic control, or both, disconnecting the drive and arresting all the moving parts of the loom, including the slay, in a short period of time corresponding to about 30 degrees or less of the crankshaft's revolution, such said stopping means being initiated automatically by reason of either the 55 shuttle failing to enter the shuttle box at the proper time or any one of a number of weft forks detecting the absence of weft in the shed at or shortly before the time when the shuttle is normally due to enter the box, and such reversing 60 means, under manual control, enabling the slay, after it has been so arrested in its forward movement, to be returned at will to its back position or thereabouts, during which return movement the crankshaft and its co-driven parts are caused 65 to make a partial revolution in the reverse direction, thereby re-opening the last shed in which the fault occurred.

The said improved driving means for looms 70 consists of a novel combination of a flywheel, a friction clutch and a friction brake, which clutch

75

and brake are controlled by a common operating lever as herein later described. While the single-plate construction of clutch and brake shown in Fig. 1 is preferred, any equivalent arrangement of frictional surfaces which may be controlled in respect to their engagement in the manner described may be utilised without departing from the principle of the invention. It is of the utmost practical importance, however, that the clutch and brake inner members shall be of light-weight construction in order to facilitate their rapid acceleration when the clutch is engaged, and, still more so, their rapid retardation when the brake is applied.

Referring to Figs. 1, 2 and 3 the flywheel 1 and clutch outer member 2, integral therewith, are mounted on a short primary shaft 3 (which may be tubular as shown or solid) which is supported in suitable bearings 4 and driven by an electric motor 5 by means of a flexible coupling 6, whereby the flywheel and clutch outer member revolve at motor speed.

A secondary shaft 7 is supported in suitable bearings 8, in axial alignment with the said primary shaft, and is further supported at the end adjacent to the flywheel by the spigot bearing 9 carried in the flywheel boss. Shaft 7 is preferably splined at 7a to receive the internally splined two part sleeve, the members 10a and 11a, of which are also externally splined to fit the internally splined hubs 10b and 11b respectively, of the clutch inner member 10 and the brake inner member 11. By this construction, the clutch and brake inner members are free to slide axially within certain limits along shaft 7 but are effectively keyed thereto.

The brake outer member 12 is prevented from revolving, and may be part of or attached by bolts to the casing 13, which serves to support the bearing end-plate 14 and to enclose the flywheel, clutch and brake. The said casing is formed with an opening at the top for access to the enclosed parts, which opening is normally closed by the cover 15.

A common shipper-sleeve 16 is slidably mounted on or concentric with the secondary shaft 7 between the clutch and the brake, and its axial movement is controlled by fork-lever 17 pivoted on pins 18a carried in the casing 13. Rocker pins 17a, carried in the said fork-lever, engage the gimbal-ring 18, which by means of rocker pins 16a, transfers the movement of fork-lever 17 to the shipper-sleeve 16. The fork-lever 17 projects downwards through a hole formed in the bottom of casing 13, and also through a corresponding hole in the subsidiary bedplate 25.

The brake presser-plate 12a is a slidable fit in the brake outer member 12, and (as shown also by Fig. 3) projections 12b on the brake presser-plate engage correspondingly shaped notches formed in the brake outer member 12, so that the said brake presser-plate is also prevented from revolving.

The clutch presser-plate 2a is similarly fitted in the clutch outer member 2, so as to revolve with the flywheel 1.

The clutch presser-plate 2a and brake presser-plate 12a are fitted with screwed rings 2c and 12c, respectively each of such rings being provided with edge-notches for C-key actuation and also with a number of spaced holes, one of which is engaged by a spring plunger 19 for locking purposes. These screwed rings are adjusted to provide the desired axial movement of the presser-plates in response to the normal rocking move-

ment of the fork-lever 17 and corresponding axial movement of the shipper-sleeve 16.

The said shipper-sleeve directly engages ring 12c screwed into the brake presser-plate 12a, as neither of these parts revolves. Ring 2c screwed into the clutch presser-plate 2a, both of which are normally revolving, is engaged by the shipper-sleeve through the anti-friction thrust bearing 20.

10 The return movement of the presser plates 2a and 12a is effected by spring plunger 21, acting on projections 2b and 12b.

As shown in Fig. 1, the brake spring 22, adjustably anchored at 22a, is acting on fork-lever

15 17, which by the means already described is causing the brake inner-member or disc 11 to be clamped between the brake presser-plate 12a and the adjacent flat surface of the brake-outer-member 12, the consequent friction acting to stop

20 shaft 7 (if this is revolving when the brake is applied), and to hold it stationary. At the same time, with lever 17 in the "stop" position shown in Fig. 1, the shipper-sleeve being displaced towards the brake, the clutch presser-plate 2a,

25 under action of its spring plungers 21, is correspondingly displaced towards the brake, whereby the clutch inner-member 10 is free from end-pressure and is not driven.

Movement of link 23 in the direction of the 30 arrow (Fig. 1) causes lever 17 to be rocked in the same direction, in the course of which movement the brake is first released and the clutch then engaged, while due to such movement the brake-spring 22 is further extended.

35 Conversely, when link 23 is released, the brake-spring 22 rocks lever 17 in the opposite direction, in the course of which movement the clutch is first disengaged and the brake then applied. When fork-lever 17 is in its midway position, the 40 brake is disengaged, but the clutch has not yet been engaged.

The necessary speed reduction from the motor-driven primary shaft to the loom crankshaft (or other driven shaft of the loom) consists preferably of an enclosed worm-gear followed by a pair 45 of spur-gears, in which case the worm-shaft becomes the said secondary shaft as shown in Fig. 1.

In the preferred construction, the casing 13, carrying the bearings for the primary shaft and 50 enclosing the flywheel clutch and brake, is bolted to the worm-gear box 24 in axial alignment with the worm-shaft 7. The motor 5 and the worm-gear box, the latter with the said casing bolted to it, are mounted on a subsidiary bedplate 25, which in turn is slidably mounted on the loom soleplate 26 at the driving end of the loom, as shown in Figs. 4 and 5.

The worm-wheel shaft 27 is extended towards the loom end-frame 28, and keyed on the said 60 shaft is a spur-pinion 29, which meshes with a spur-wheel 30 keyed on the projecting end of the loom crankshaft 31, which is provided with an outer bearing 32 mounted directly on the loom soleplate 26.

65 In order that the loom may be readily adjusted to run at its optimum speed, arrangements are included to facilitate changing the spur-pinion 29 for another having a different number of teeth, in which case, the spur-gear centre distance is 70 adjusted to suit by sliding the subsidiary bedplate 25 along the loom soleplate 26 in a line parallel to the loom end-frame 28. When the spur-gear centres have been correctly adjusted in this manner, the subsidiary bedplate 25 is bolted down 75 to the loom soleplate 26, as indicated at points

25a, where the bedplate is provided with slotted bolting-down lugs. Guide strips are preferably provided, as indicated at 26a in Figs. 2 and 5, to maintain the bedplate and soleplate in correct relative alignment, also screw adjustment as shown at 26b, in Figs. 4 and 5, as a means for adjusting and maintaining the correct centre distance for the spur-gears.

The worm-wheel shaft 27 is provided with an outer-bearing 27a, carried on, so as to move with, the subsidiary bedplate 25.

The above described driving and stopping gear is normally controlled by manual operation of the usual long control rod 35 extending the full width of the loom along the breast rail. The said control rod is hinged to the starting lever, and both are retained in their "run" positions by locking over a primary toggle included in the linkage connecting the starting lever to the fork-lever for actuating the clutch and brake. Automatic stopping is achieved by tripping (in any suitable manner) a secondary toggle or toggle-pair also included in the said linkage, upon which tripping action the loaded brake-spring acts almost instantaneously to disengage the clutch and apply the brake, during which action the long control rod and starting lever remain stationary in their "run" positions, with the advantageous result that the very appreciable retarding action caused, in known construction, by their inertia is entirely eliminated, and consequently the time taken to bring the brake into action is correspondingly and very appreciably reduced.

By the described means comprising the said clutch and brake acting on a shaft normally running at the speed of the electric motor used to drive the loom, in combination with the said practically instantaneous tripping action of the secondary toggle for effecting disengagement of the clutch and full application of the brake, the whole of the moving parts of the loom are arrested and brought to a standstill in a short period of time corresponding to about 30 degrees or less of the crankshaft revolution, and without injurious shock, while the motor then continues to drive the primary shaft together with the flywheel, the clutch outer member and the clutch presser-plate, the stored energy of which assists the motor to bring the loom very quickly to its normal running speed when the clutch is again engaged.

Referring to Figs. 6a, 7a and 8a, the long horizontal control rod 35 is pivotally connected to the long arm 36a of the starting lever 36, which is of bell-crank form. This lever is pivoted at 36c on a bracket 37 bolted to the end-frame 28 at the driving end of the loom. When the starting lever 36 is pulled over by means of the control rod towards the end-frame, the projection 36d finally abuts against a stop-screw 38b carried in the bracket 37, the starting lever being then in the "run" position as shown by Fig. 8a, when its short arm 36b extends approximately horizontally towards the end-frame 28.

A transmission lever 38, also of bell-crank form, is pivoted at 39c, on the loom end-frame. The horizontal arm 39a of the said transmission lever extends outwardly from the end-frame and its outer end is connected by any suitable linkage to the link 23 and fork-lever 17 which actuate the clutch and brake. The top end of its vertical arm 39b is substantially in horizontal alignment with the starting lever pivot 36c, and is connected to the short arm 36b of the starting lever by two links 40 and 41 which are suitably

constructed and centrally hinged together at 40b to form the aforesaid secondary toggle or toggle-pair.

Their own weight tends to keep the two links 40 and 41 in their locked position as shown in Figs. 7a and 8a, when the central hinge pin 40b is just below a straight line passing through the two end pivot pins 36b and 39b, such locking action being limited by a finely adjustable stop-screw 40a.

The brake-spring 22 (Fig. 1) acting through link 23 and connected by any suitable intermediate linkage to the vertical link 34, which is connected to and actuated by the transmission lever 38, acts to maintain the said toggle pair in compression and, therefore, in their locked position as above described, and consequently throughout all manual operation of the control rod 35 for normal starting and stopping purposes, the said toggle pair acts as a simple compression link connecting the short arm 36b of the starting lever to the upright arm 39b of the transmission lever. Thus, when the control rod is manually moved, together with its connected starting lever, from their "stop" position, shown by Fig. 7a, to their "run" position shown by Fig. 8a, the short arm 36b swings down approximately to the horizontal, while, due to the locked toggle pair 40 and 41, then acting as a simple compression link, the upright arm 39b of the transmission lever is forcibly displaced towards the loom end-frame and its horizontal arm 39a is correspondingly raised, whereby, against the opposing pull of the brake-spring 22, the brake is first released and the clutch then engaged to start the loom. As the starting lever completes this movement and the projection 36d abuts against the adjustable stop-screw 38b its short arm 36b forms a toggle lock (the aforesaid primary toggle-lock) in combination with the said locked toggle-pair 40 and 41 which are still acting as a simple compression link, and consequently the starting lever is locked in the "run" position against the pull of the brake-spring, as shown in Fig. 8a.

Initial manual movement of the control rod 35 in the opposite direction unlocks the said primary toggle, when the brake-spring acts to return, or to assist in the manual return of the parts to the "stop" position, shown by Fig. 7a, whereby the loom is stopped.

When the parts are locked in their "run" position as above described and shown in Fig. 8a, the brake-spring may be allowed to disengage the clutch and apply the brake very rapidly indeed by tripping the locked toggle-pair 40 and 41, during which tripping action the control rod 35 and the starting lever 36 remain completely stationary in their "run" positions, while as shown in Fig. 6a, the tripped toggle-pair collapses in an upward direction thus allowing the brake-spring to act as above described.

The said toggle pair, after it has been tripped automatically to stop the loom, is readily restored to its locked position by simple manual return of the control rod 35, together with its attached starting lever 36, to the "stop" position, as shown by Fig. 7a, in the course of which movement the links 40 and 41, comprising the toggle pair, straighten out and then, due to their own weight, resume their locked position in readiness for re-starting the loom.

In some cases, the long control rod 35 may be dispensed with and the starting lever 36 fitted with a suitable handle for direct manual operation.

The intermediate linkage connecting the fork-lever 17 to the horizontal arm 39a of the transmission lever may take any convenient form, such as that illustrated in Figs. 4 and 5, wherein, the link 23 (connected to the fork-lever 17 as shown in Figs. 1 and 2) extends through a hole in the end of the subsidiary bedplate 25 and is pivotally and adjustably connected to lever 33, which is itself pivoted at 33x. A loaded compression spring 23a is preferably fitted to the outer end of link 23 so as to cushion the clutch engagement and follow-up slight wear of the frictional surfaces of the clutch inner member 10. The effective length of link 23 is adjusted by means of locknuts 23b when the position of the bedplate 25 is changed to suit a different size of pinion 29 fitted to shaft 27. The lever 33 is thence connected by the horizontal link 33a to a lever 33b secured to the rocker-shaft 33c, while the lever 33d, also secured to the said rocker-shaft, is connected by a vertical link 34 to the horizontal arm 39a, of the said transmission lever 39.

The above described secondary toggle or toggle pair 40 and 41 may be automatically tripped in the event of the shuttle failing to enter the shuttle-box and open out the swell at the proper time, whereby, as already described, the whole of the moving parts of the loom, including the slay, are brought to a standstill by the said friction brake in a very short period of time corresponding to about 30 degrees or less of the crank-shaft's revolution, with the slay having moved through little more than the first half of its forward movement, so dispensing with the use of, and the attendant troubles caused by the customary dagger and frog mechanism as a direct means of arresting the forward movement of the slay.

In the construction preferred for attaining such automatic stoppage of the loom, a light stop-rod 42 (see Figs. 9, 10 and 10a) mounted on the slay 43 and controlled by a spring 44 and feeler levers 45 adapted to rest against the shuttle-box swells 46 in the usual manner, is provided with a light dagger blade or dagger 47, which is freely hinged on the said stop-rod 42 near the driving end of the loom. The dagger 47 is supported and its angular position thereby controlled by an adjustable dog 48 secured to the stop-rod alongside the dagger.

When the slay 43 is moving forward and neither of the boxes contains a shuttle, the dagger 47 is adapted, at a suitable point in the slay's forward movement, to engage and displace a trip-lever 50 (see Figs. 8a and 8b) pivoted on a vertical axis under the breast rail 28a near the end-frame 28 at the driving end of the loom.

If, however, during the slay's forward movement the shuttle enters the shuttle-box at the proper time, the swell 46 at the front of the box is opened out, and, as shown by dotted lines in Fig. 10, the feeler-lever 45 resting thereon rocks the stop-rod 42 together with the dog 48 secured thereon with the result that the front end of the dagger 47 is lowered so as to pass below the trip-lever 50 without engagement, in which case the loom continues in motion.

The trip-lever 50, pivoted at 50c, is provided, as shown by Figs 6a to 8b, with a short arm 50a which is connected by a short horizontal link 51 to a lug or arm 41a formed solid with link 41 of the aforesaid secondary toggle or toggle-pair in such a manner that when the slay 43 is moving forward and for the stated reason (or for any other reason causing the dagger to be held

up in its engaging position) the dagger 47 engages with and displaces the trip lever 50, the first part of such displacement (in practice, equal to a small fraction of an inch) serves, by link connection 51, to unlock and trip the toggle-pair 40 and 41, (as shown in Fig. 6a) thereby stopping the loom by the retarding action of the brake with the slay having moved through little more than the first half of its forward movement, thereby preventing damage to the warp, the reed and the shuttle in the event of the latter remaining in the shed.

The collapsing movement of the two links 40 and 41 comprising the toggle-pair, swings the trip-lever 50 around out of the path of the dagger 47, as shown by Figs. 6a and 6b, in which position the trip-lever offers no obstruction to the free oscillation of the dagger, together with the stop-rod and its feeler levers, during subsequent manual insertion of a shuttle into one of the empty boxes in preparation for restarting the loom.

After the toggle-pair has been restored to its locked position, in the manner already described, and the control rod is again moved into the "run" position to start the loom, the link 51 causes the trip-lever 50 to swing back to its operative position, as shown in Figs. 8a and 8b.

The dagger 47 may be held down against the dog 48 by a spring 47a to ensure the dagger following the rapid downward angular movement of the dog. The use of the dagger freely hinged on the stop-rod and positively controlled only in the upward direction by the dog secured to the stop-rod, in the manner already described, serves to prevent damage to the stop-rod and its attached parts if the dagger has already engaged the trip-lever when the shuttle enters the box later than normal.

With the same general effect, the dagger 47 may be secured directly to the stop-rod 42, so dispensing with the dog 48, if so desired.

The above described automatic stopping action in the event of the shuttle failing to enter the shuttle-box at the proper time, may be made further conditional upon any one of a number of weft-forks, suitably spaced along and supported on the slay, detecting the absence of weft in the shed at or shortly before the time when the shuttle is normally due to enter a box, in which event, the stop-rod dagger is retained in its upper or engaging position (even though the shuttle duly enters the box at the proper time) and by actuating the trip-lever effects prompt stoppage of the loom as already described.

In the preferred construction of such weft stop-motion, the details of which may be varied without departing from the principle of the invention, two weft-forks are spaced on the slay at a distance from each end equal to about one third of the reed-width. These two weft-forks are actuated in unison by a cam 31a on the loom crankshaft 31, in the particular manner herein later described.

Referring to Figs. 11, 11a, 12, 13 and 14, each weft-fork consists of a fork-head or boss 52 pivoted at 53c in a stand 53 fixed to the front face of the slay 43, the said boss having provision for clamping therein or thereto one or more wire prongs 54, which project from the boss towards the reed. The shuttle race and slay are slotted to form a recess opposite each fork in the usual manner as shown at 43a.

Midway in its length, the boss 52 takes the shape of a pushing pawl, the nose 52a of which

projects towards the slay and swings up and down in step with the fork-prongs, but at a smaller radius.

On the same side as the projecting pawl, the fork-boss is also provided with a short arm 52b, by which the fork is positively oscillated, and also with a lug 52d for the attachment of a light spring 55, the lower end of which is adjustably anchored to the stand or any other suitable anchorage, but preferably to the front end 57a of lever 57.

A light rocker-shaft 56, by means of which the two forks are oscillated in unison, is supported in bearings 53a mounted on the slay below the stop-rod 42, such bearings preferably forming part of the stand 53. Opposite each stand, the shaft 56 has secured to it a forwardly projecting lever 57, to the forward end 57a of which the bottom end of a link 58 is pivotally and adjustably connected, such pivot having only ordinary working clearance. The top end of the said link has an elongated hole which engages pin 52c in the short arm 52b on the fork-boss. The said elongated hole corresponds to a free movement of the boss and fork-prong 54 of about 10 degrees, and its action is illustrated in Figs. 12a, 13a, and 14a.

The rocker-shaft 56 is oscillated by a cam 31a on the loom crankshaft 31 (Fig. 15), the motion of the cam follower lever 31b being transmitted to the shaft 56 by any suitable levers and links such as link 31c, bell-crank lever 31d, link 31e and slotted lever 59. The return movement of the said levers and links is effected by a strong spring 31f, which serves to maintain the bowl of the follower lever in contact with the cam profile. A spring 58a fitted to the lower end of each link 58 acts as a spring escapement, the purpose of which is to prevent damage to the parts should the positive downward movement of either fork be obstructed, for example, by the shuttle.

By the action of cam 31a, the forks 54 remain down in their recesses 43a during the beat-up, and, as the slay moves back, they are positively raised through an angle of about 60 degrees by the time the shuttle is normally due to enter the shed, as shown in Figs. 14 and 15. As shown in Fig. 14a, the bottom end of the elongated hole in the top end of link 58 engages pin 52c during the fork's upward movement.

The forks remain in such raised position until the shuttle has reached the second of the two forks (counting from the picking end), at which time both forks are positively and very rapidly lowered (subject to the aforesaid escapement springs 58a compressing in the event of dangerous obstruction) thereby readily overcoming the frictional resistance offered to such fork movement by a strong and dense warp, to the position shown in Fig. 11a, hereinafter referred to as the detecting position, in which the fork prongs 54 are parallel to and just below and clear of the warp yarn forming the bottom shed. As shown in Fig. 12a, the pins 52c in the fork-arms 52b are engaged by the top ends of the elongated holes in links 58 during this positive downward movement of the forks into their detecting position. Upon completion of this movement, the cam bowl enters upon a dwell period on the cam profile.

The forks in their detecting position being just below and clear of the bottom shed, and furthermore, by reason of the elongated holes in the top ends of their now stationary actuators

ing links 58, are mechanically free to descend under the pull of their light springs 55, through a further angle of about 10 degrees, in which case pins 52c will descend to the bottom end of the elongated holes. The forks descend in this manner, unless each fork is independently sustained in the detecting position by its prong or prongs being effectively supported by the weft, which if present, prevents such downward movement as shown in Fig. 12.

The forks are made as light in weight as possible consistent with necessary strength so that when weft is absent their conditional further downward movement below their detecting position (shown in Figs. 13 and 13a) occurs practically instantaneously under the action of the light spring 55 fitted to each fork. As will be later described the position occupied by the forks 54 and their associated pawls 52a, immediately after these have been positively lowered to their detecting position, and before or at the time when the shuttle is normally due to enter the box, determines whether the loom is to continue in motion or is to be stopped automatically in the manner already described.

Referring to Figs. 11 and 11a the light stop-rod 42, hereinbefore described, is fitted with a tubular sleeve 60 which is free to turn on and independently of the stop-rod when necessary. The length of the said sleeve is such that it extends from the dagger 47 freely hinged on the stop-rod 42 at the driving end of the loom to the more distant of the two weft-fork stands 53. At the driving end the sleeve has secured to it the adjustable dog 48 which supports and controls the angular position of the dagger 47 in a manner similar to that already described, while secured to the other end of the sleeve is a lever or arm 61 which engages a corresponding lever 62 secured to the stop-rod 42. These two levers are held in contact by escapement spring 62a, by which means the sleeve 60 normally tends to rock in step with the stop-rod 42. The action of these levers and their connecting spring is shown by Figs. 12b and 13b.

With continued reference to Figs. 11 and 11a, also secured to the said sleeve, opposite each fork-stand and in alignment with each fork-pawl 52a, is a vertical lever 63, the top end 64 of each such lever being adjustable for height and adapted to engage the end of its associated fork-pawl 52a if and when this descends below the detecting position, as shown in Fig. 13, due to the absence of weft.

When the stop-rod 62 is rocked by its spring 44 in consequence of its feeler levers 45 moving in to rest on the swells 46 of the empty shuttle boxes, as occurs immediately the shuttle is picked, the stop-rod, by means of the levers 61 and 62, rocks the sleeve 60, so that the dog 48 secured thereon rises and lifts the dagger into its engaging position, while at the same time the vertical levers 63 swing back (towards the front face of the slay) into such position, shown in Figs. 11a and 13, as allows their forward return movement to be conditional upon the action of the weft-fork pawls.

When the stop-rod 42 is rocked in the opposite direction, due to the shuttle entering the box after crossing the loom, the sleeve 60 is correspondingly rocked so as to lower the dog and the dagger to its clearing position, provided that, at the time the shuttle enters the box, both forks and their pawls 52a are sustained in their detecting position due to the fork prongs 54 rest-

ing on the weft present in the shed. In such case, as shown by Fig. 12, the top ends 64 of the vertical levels 63 pass freely below, without obstruction by, the fork-pawls 52a, and the loom continues running. During such normal action, the sleeve 60 and stop-rod 42 rock together, also levers 61 and 62, as shown in Fig. 12b.

In the event, however, of weft being faulty or absent, and the consequent descent below the detecting position of either of the two pawls, (or both of them) its associated vertical lever 63 is obstructed and, together with the sleeve 60, is held stationary when the stop-rod 42 rocks due to the shuttle entering the box, as shown in Fig. 13. The dog 48 secured to the sleeve 60, thus prevented from rocking, retains the dagger 47 in its upper or engaging position, with the result that the loom is promptly stopped in the manner already described with the slay having moved through little more than the first half of its forward movement.

During such action, the sleeve remains stationary while the stop-rod rocks inside it, and lever 61 remains stationary while lever 62 rocks with the stop-rod, such relative movement of the said levers causing spring 62a to be further compressed as shown in Fig. 13b. This spring escapement acts, therefore, to prevent damage to the parts involved when the stop-rod rocks due to the shuttle entering the box, but the sleeve is held stationary by a fork-pawl descending due to the absence of weft. The details of the said spring escapement may be varied if desired, to make use of a tension spring or torsion spring instead of the compression spring shown.

The dagger 47 may be held down against the dog 48 by a spring 41a as already described in reference to Fig. 10a. With the same general effect, the dagger may be secured to the end of the sleeve 60, so dispensing with the dog, if so desired.

It will be understood that the loom is automatically stopped in the course of its forward movement and with the reed a suitable distance from the fell of the cloth to avoid damage caused by a trapped shuttle, and also well before a faulty weft pick is beaten into the cloth (as shown by Fig. 17), unless:

(i) the shuttle enters the box at the normal time in the crankshaft's revolution or within the permissible tolerance thereof, and

(ii) both forks independently detect the presence of weft in the shed at or shortly before the time the shuttle enters a box.

Only one weft-fork stand is shown in Fig. 11, and a second and identical stand will usually be interposed between the one shown and the driving-end slay sword 49, the said two stands being spaced apart as already described.

While this part of the invention has been described in respect to two weft-forks, one or more such forks may be fitted to the loom, according to requirements or preference. Provision is made for adjusting the timing of the cam 31a on the crankshaft 31 so that the downward movement of the forks towards their detecting position may commence as early as possible but, of course, without obstructing the shuttle's passage.

Fig. 16 is a typical timing diagram for the improved stop-motion as applied to a wide loom. The front and back centre positions of the crankpin are indicated respectively at FC and BC. With the crankshaft normally revolving in the direction shown by the arrow, the weft-forks com-

mence their upward movement at a and complete the same at d. The pick occurs at b and the shuttle enters the shed at c, passes the first weft-fork at e and the second weft-fork at f, when the weft forks commence their rapid and positive downward movement, arriving at the detecting position at g. The shuttle normally enters the box at h, but if it fails to do so, the dagger 47 engages the trip-lever 50 at i, with the result that the clutch is disengaged and the brake is applied at about j, so that the crankshaft is brought to a standstill at k.

Even if the shuttle enters the box in the normal manner h, but one (or more) of the weft-forks detects the absence of weft in the period g to h, the dagger engages the trip-lever at i, and the crankshaft is stopped at k.

The positions a, d, f, and g on the cam 31a shown in Fig. 15, correspond with the similarly marked positions in Fig. 16.

When the slay has been arrested in its forward movement, together with all other moving parts of the loom, in consequence of either the shuttle failing to enter the box at the proper time and/or the absence of weft as detected by one or more of a number of weft-forks in the manner already described, the slay may be returned to its back position, and the crankshaft concurrently reversed together with its co-driven parts so as to re-open the last shed in which the fault occurred, thereby facilitating repair of the weft and/or other necessary adjustments preparatory to continuing weaving.

Referring to Fig. 17, the slay 43 is carried on multiple swords 49 pivoted at 65, which swords are oscillated by the crankshaft 31 through well-known linkage comprising connecting rod 66 engaging crankpin 31g, radius arm 67 and link 68. All these parts, including the slay, are shown in the position they occupy when the crankshaft has been stopped automatically in the above described manner.

Each sword 49 has attached to it one or more long springs 69, the rear ends of which are suitably anchored to the loom structure as at 69a. The said springs are adjusted to exert a suitable backward pull on the slay when this is fully back, which pull increases in a certain degree depending upon the dimensions of the springs, as the slay moves forward.

After the slay has been stopped in its forward movement, a partial movement of the control rod 35 (or, if a control rod is not used, of the equivalent starting handle), releases the brake without engaging the clutch, thereby allowing the said springs 69 to return the slay to its back position; or thereabouts, in the course of which movement the crankshaft 31 and all its co-driven parts are correspondingly reversed, with the result that the last shed in which the fault occurred (and initiated automatic stoppage) is re-opened.

A similar effect may be obtained by the attachment of weights 70 to arms 71 extending to the rear of and carried on the slay swords 49, but the additional inertia of these added weights is objectionable in some degree, more particularly in respect to the prompt arrest of the slay's forward movement. This objection is not serious, however, in the case of very wide looms which necessarily operate at relatively low speeds. The said objection does not apply to the above described use of springs, which, therefore, may be applied to faster running looms for the above specified purpose.

Figs. 18 to 24 illustrate the means already referred to as forming an object of the invention for arresting the moving parts of the loom should either set or both sets of the drop shuttle boxes jam during their change movement.

In these drawings the parts referred to by numerals correspond with the parts referred to by the same numerals in Figs. 1 to 17, the parts referred to by small letters relate to parts of the known box-motion and safety escapement, and the parts referred to by capital letters are those forming the novel features of the motion for arresting the moving parts of the loom should the boxes jam.

Referring to Figs. 18 to 22 the link-rod *a*, which is actuated by the usual box-selector mechanism (not shown), is adjustably connected to the slotted lower arm *b*¹ of the sector-lever *b*. This latter lever is adapted to rock freely on the fixed axle *c*, which is suitably supported in the loom end-frame *23* and by the standard *d*.

The box-lever *e*, which also is free to rock on the said axle, is normally rocked by and in step with the said sector-lever by means of the safety escapement shown, when this latter is engaged. The rearward arm *e*² of the box-lever *e* is pivotally and adjustably connected to link *f*, the bottom end of which is suitably adapted for connection to the box-lifter (not shown) by which the angular oscillating movement of box-lever *e* is conveyed to the shuttle-boxes carried on the slay in the usual manner. The slay swords are pivoted at 65.

The periphery of the sector *b*² or top arm of the sector-lever *b*, is provided with a recess *b*³ of approximately semi-circular outline, such recess being normally engaged by escapement-bowl *h* carried on escapement-lever *g*, which is freely hinged on pin *e*³ fixed in the forward arm *e*¹ of the box-lever. The escapement-bowl *h*, carried on pin *h*¹ fixed in the said escapement-lever, is pressed into the sector recess by means of the adjustable spring *i*, which extends between the escapement-lever and the box-lever in the manner shown.

As shown in Fig. 18, the said escapement is normally engaged, and movement of the link-rod *a* in the direction indicated by the arrow causes all three levers, viz: the sector-lever *b*, the escapement lever *g*, and the box-lever *e*, to rock as one solid unit on the axle *c*, whereby the shuttle-boxes are lowered. Movement of the link-rod in the opposite direction causes the shuttle-boxes to be lifted as shown in Fig. 19.

Figs. 18, 19 and 20 show only two angular positions of the box motion transmission levers, corresponding to a set of boxes having only two cells, but the motion is equally adaptable for operating boxes with three, four or more cells.

If the positive movement of the boxes is obstructed by a misplaced shuttle or picker, the consequent overload to which the said mechanism is thereby subjected causes the escapement-bowl *h* to be forced up and out of the sector recess *b*³ in the manner shown by Fig. 20, so disconnecting the box-lever *e* from the sector-lever *b*.

The escapement lever *g* may be extended to the front of its pivot *e*³ and formed into a foot-pedal *g*¹ by which the escapement-bowl *h* may be manually withdrawn from its recess to disconnect the said levers as may be necessary when the loom is stationary. Such pedal arm may be further provided with setscrew *g*² adjusted to abut against lug *e*⁴ on the box-lever *e* when the bowl *h* is fully withdrawn from its recess *b*³ in

which case further downward movement of the foot-pedal *g*¹ lifts arm *e*² of the box-lever *e*, and causes the shuttle-boxes to be lifted, thereby facilitating release of a jammed shuttle, or any other necessary adjustment.

According to the present invention, the aforesaid automatic displacement of the escapement-bowl *h* from its recess *b*³, that is, from its normal radius of action, while the loom is running, is caused, by means of suitable mechanical connections of any convenient form, to trip the aforesaid secondary toggle or toggle-pair comprising the links 40 and 41, and thereby promptly to stop the loom as hereinbefore described.

Such mechanical connections are shown by Figs. 21, 21a, 22 and 23 in which a feeler-lever *A* is pivoted at *A*¹ on a bracket *A*² secured to the axle *c*. The outer end *A*³ of the feeler-lever *A* is adapted to engage a trip-bowl *B*, mounted on the pin *h*¹ and, therefore, in axial alignment with the escapement-bowl *h*. The outer end *A*³ of feeler-lever *A* is splayed out and also cambered on its under-side as shown in Figs. 21 and 21a, so that the trip-bowl *B*, at any position in its normal angular movement around axle *c*, may lift the outer end *A*³ of the feeler-lever in the event of the escapement-bowl *h* being forced out of its driving recess *b*³.

Such movement of the feeler-lever *A* is conveyed to a rock-shaft *E* by a vertical link *C* which connects the inner end *A*⁴ of the feeler-lever to the forwardly projecting arm *D*¹ of lever *D* secured to the adjacent end of the said rock-shaft. Also secured to this shaft is the finger-lever *F*, which is adapted to engage the drop-arm *T* extending downwards from the trip-lever 50. The finger-lever *F* has a rearwardly projecting lug *F*¹, to which one end of a spring *F*² is attached, the other end being anchored on the loom frame as at *F*³.

The said rock-shaft *E*, which is supported in suitable bearings in the loom intermediate and end frames, extends to the other end of the loom, where another lever similar to *D* is secured to the rock-shaft, such lever being actuated in a corresponding manner to rock the shaft should the box-motion escapement at that end automatically disengage.

The spring *F*² acts to hold the rock-shaft *E* in its ready position (as shown in Figs. 22 and 23) in which the top end of the finger-lever *F* is close to or in contact with the drop-arm *T* on the trip-lever 50, (when this is in its normal operative position as shown), and, at the same time, the cambered ends *A*³ of the feeler-levers *A* rest on their respective trip-bowls *B* at each end of the loom.

If, for the stated or any other reason, the escapement bowl *h* is forced out of its recess, so that the effective radius of its pin *h*¹ from the centre of axle *c* is thereby increased, such displacement is shared by the co-axially mounted trip-bowl *B*, which rocks the feeler-lever *A* and by the connections described rocks the shaft *E* in the direction indicated by the bent arrow Fig. 23 during which angular movement the finger-lever *F* acts on the drop-arm *T* and turns the trip-lever 50 around its vertical axis 50c, with the result that by means of the link connection 51, the secondary toggle, comprising the links 40 and 41, is tripped, the said links collapsing in an upward direction, while the bell-crank lever 39 is rocked and its arm 39a is lowered under the pull of the brake spring acting through link 34, whereby the driving clutch is disengaged

and the brake is applied as hereinbefore described.

The loom is thus automatically and promptly stopped if the box-motion safety escapement disengages either at one end or at both ends simultaneously. In such event, the escapement bowl *h* is sufficiently displaced in the position shown by Fig. 20 for the correspondingly displaced trip-bowl *B* to actuate the trip-lever 50 and to trip the secondary toggle. In Fig. 20 the box-lever *e* has been impeded very early in its intended movement, and the sector-lever *b* has continued its movement to about half-way in its normal swing, corresponding to the cranks being in their front centre position when the slay is in its most forward position.

Referring to Fig. 24 which is a timing diagram, typical for a wide loom, the shuttle-boxes commence to change at I and are normally half-changed at the crank front-centre FC. The boxes normally complete their change at IV. The next pick occurs at V, after which the shuttle enters the shed at VI and arrives in the opposite box at VII.

If the movement of the shuttle-boxes, during their change, is obstructed, however, the escapement-bowl *h* is displaced (as in Fig. 20) and the secondary toggle is thereby tripped at FC, by which action the clutch is disengaged and the brake fully applied at II. The crankshaft stops within the range III to IV, that is, well before the next pick is due to occur at V.

I claim:

1. In a weaving loom the combination with the crankshaft of the loom and a motor by which it is driven of a short primary shaft driven by the motor, a flywheel and one member of a friction clutch affixed on the primary shaft, a secondary shaft driving the crankshaft, reduction gear between the secondary shaft and the crankshaft, a sleeve rotating with the secondary shaft but slideable thereon, a second member of the friction clutch secured on the sleeve, one member of a friction brake also secured on the sleeve, a stationary member of the brake co-axial with the first member, the member of the clutch and the member of the brake being secured on the sleeve in such positions that when the members of the clutch are engaged the members of the brake are disengaged and vice versa and means capable of both manual and automatic control for moving the sleeve axially on the secondary shaft.

2. A weaving loom as in claim 1 having a spring tending to move the sleeve in a direction to engage the brake members and disengage the clutch members.

3. In a weaving loom as in claim 2 the combination with the loom weft feeler mechanism of linkage controlled by said mechanism and connected to the means operating the sleeve on which the moveable clutch member and the moveable brake member are mounted whereby on the feeler mechanism coming into operation

the sleeve will be moved to disengage the clutch and then apply the brake.

4. A weaving loom as in claim 1 having a starting lever, weft feeler mechanism, linkage connecting the starting lever to the sliding sleeve, a spring tending to move the sleeve in a direction to engage the brake members and disengage the clutch members, a primary toggle pair arranged in said linkage for retaining the starting lever in the position for the normal running of the loom, a secondary toggle pair arranged in said linkage, and means controlled by the weft feeler mechanism of the loom for tripping the second toggle pair to allow the spring acting on the sleeve to move the latter to disengage the clutch and apply the brake on the weft feeler mechanism coming into operation.

5. A weaving loom as in claim 4 having means for tripping the second toggle pair should the shuttle fail to enter the shuttle box.

6. A weaving loom as in claim 5 the combination with loom slay and the shuttle box swell, of a stop rod rotatably mounted on the slay, a spring controlling the stop rod, a dagger blade hinged on the stop rod, an adjustable dog also mounted on the stop rod for controlling the angular position of the dagger blade on the rod, feeler levers mounted on the stop rod and resting on the shuttle box swell, the feeler levers rocking the stop rod at each forward movement of the slay if the shuttle box swell is opened out by the pressure of a shuttle in the box, and a trip lever connected to one member of the second toggle pair, the trip lever being engaged by the dagger

35 to unlock the toggle pair and so disengage the clutch members and engage the brake members, when the stop-rod is not rocked by the feeler levers owing to there being no shuttle in the box.

7. A weaving loom as in claim 6 having shuttle boxes of the drop box type, having in combination with the shuttle box, means whereby the secondary toggle pair will be tripped to cause the stoppage of the loom should the shuttle box jam during its change movement.

8. A weaving loom as in claim 7 having a mechanical linkage between the usual box motion safety escapement and the secondary toggle pair whereby on the safety escapement coming into operation the toggle will be tripped, the clutch disengaged and the brake applied.

THOMAS HINDLE.
